UNITED STATES PATENT OFFICE.

ELLEN M. PRESTON, OF PROVIDENCE, RHODE ISLAND, ASSIGNOR OF ONE-HALF TO HERBERT I. GOULD, OF SAME PLACE.

NAPKIN-BELT.

SPECIFICATION forming part of Letters Patent No. 423,572, dated March 18, 1890.

Application filed July 1, 1889. Serial No. 316,259. (No model.)

To all whom it may concern:

Be it known that I, ELLEN M. PRESTON, a citizen of the United States, residing at Providence, in the county of Providence and State 5 of Rhode Island, have invented certain new and useful Improvements in Safety-Belts; and I do hereby declare the following to be a full, clear, and exact description of the invention, such as will enable others skilled in the art 10 to which it appertains to make and use the same.

My invention has for its object to produce a novel safety-belt for supporting a napkin, and especially to provide an article of this class 15 which will be comfortable to wear, which shall be provided with fastening devices at one or both sides, so that the belt may be readily removed, and which shall be provided at both front and back with a simple and easily-operated 20 device for the attachment of a napkin, the article being so constructed that the fastening devices cannot come in contact with the person of the wearer in use, and the fastening devices so constructed that they may 25 be readily connected to or detached from the belt at either front or back without removing them from the napkin.

With these ends in view I have devised the simple and novel construction of which 30 the following description, in connection with the accompanying drawings, is a specification, numbers being used to denote the several parts.

Figure 1 is a perspective of my novel safety-belt, showing a napkin applied as in use; Fig. 2, a section on the line *x*-*x*, showing the manner in which the napkin is attached to the belt; Fig. 3, a view of the attaching device separated from the belt; and Fig. 4 is a view 40 illustrating the substitution of a buckle for buttons as fastening devices for the belt.

1 denotes the belt, which may be made entirely of textile material or provided with strips 2 of elastic, inserted as shown in the 45 drawings. The belt in shape is not a perfect zone, but is made to curve downward and then upward again, as at 3, at both front and back, the object of this construction being to cause the weight to be entirely supported by 50 the hips, so as to avoid strain either upon the back or the abdomen. At both front and back

are downwardly-extending tabs, which I have designated as 4, the purpose of which will be presently explained. The belt may be made in either one or two pieces, preferably two, 55 as shown in the drawings, said pieces being connected at the sides in any suitable manner—for example, by buttons 5, as shown in Fig. 1, or by buckles 6, as in Fig. 4.

7 denotes the napkin, and 8 the fastening 60 devices by which it is connected to the belt at both front and back. These fastening devices consist simply of plates of metal provided with slots 9, through which the securing-straps 10 are passed, and upper and lower slots, (denoted, respectively, by 11 and 12,) through 65 which the napkin is passed in securing it in place in the manner which I will presently explain. The securing-straps are stitched firmly to the tabs, as indicated in Fig. 2, and the fastening devices are held in place by simply passing the straps through slots 9, and then connecting the free ends of the straps to the tabs in any suitable manner, as by a button 13 engaging a suitable button-hole, as 70 shown in the drawings.

It will of course be apparent that buckles may be substituted for buttons, if preferred. Each end of the napkin is secured to one of the fastening devices by passing the end 80 through slot 11 from the front and then downward and through slot 12 from the back, the end of the napkin lying underneath, as is clearly shown in Fig. 2.

In use the napkin may be attached either 85 before or after the belt is put on. Suppose the belt to be on. Each end of the napkin is connected to one of the fastening devices in the manner described. The securing-strap at the back is passed through a slot 9 in one of 90 the fastening devices and then secured in place, the other end of the napkin being then drawn to the front and connected to the belt in the same manner.

It should be noted as an important feature 95 of my invention that the fastening devices may be readily disconnected from the belt without removing them from the napkin, which is a very great convenience in use.

Having thus described my invention, I 100 claim—

A safety-belt curved downward at front and

back to place the strain upon the hips and provided at front and back with securing straps 10, whose free ends are adapted to button upon the belt, in combination with fastening devices for a napkin having slots 9, through which said straps are passed and the ends connected to the belt, so that either end of the napkin may be detached from the

belt without detaching the fastener from the napkin.

In testimony whereof I affix my signature in presence of two witnesses.

ELLEN M. PRESTON.
